(57) **CLAIM**

The ornamental design for a tray for an oval package for sliced food, as shown and described.

DESCRIPTION

FIG. 1 is a top, front and side perspective view of a tray showing my new design;

FIG. 2 is a top plan view thereof;

FIG. 3 is a front elevational view thereof, the rear elevational view being identical to the front elevational view; and,

FIG. 4 is a sectional view taken along the line 4—4 in FIG. 2.

1 Claim, 2 Drawing Sheets

FIG. 1

FIG. 2

FIG. 3

FIG. 4
